UNITED STATES PATENT OFFICE.

HARVEY R. NEWQUIST, OF WAUSA, NEBRASKA.

ELECTRICALLY-OPERATED SIGNAL FOR MAIL-BOXES.

1,307,305.

Specification of Letters Patent. Patented June 17, 1919.

Application filed April 20, 1917. Serial No. 163,512.

To all whom it may concern:

Be it known that I, HARVEY R. NEWQUIST, a citizen of the United States, residing at Wausa, in the county of Knox, and State of 5 Nebraska, have invented certain new and useful Improvements in Electrically-Operated Signals for Mail-Boxes, of which the following is a specification.

This invention relates to improvements 10 in mail box signals, and more particularly to electrically operated signals of this character for use in connection with rural delivery boxes.

The main object of this invention is to 15 provide a simple and practical mail box signal which will last for years without expense and in which the indicator of the signal will remain set until the mail is removed from the box.

20 Another object is to provide an apparatus of this character which can be cheaply manufactured and installed, and when once installed, no further expense will be incurred in the use thereof, as it is constructed 25 to dispense with the use of a battery and bell, thereby avoiding defects incident to the resistance in the wire occasioned by the use of long stretches of wire which are necessary to cover long distances between 30 the box and the point where the signal is to be given; and which also avoids the expense occasioned by the running down of batteries owing to short circuiting.

Another object is to so construct an apparatus 35 of this character that the operation thereof will be equally effective at long or short distances.

Another object is to provide a signal mechanism operatively connected to a rural 40 delivery box and operable by the opening of the mail box to place the apparatus in condition to set the signal to indicate that the box has been opened, by the passage of a current through the electrical circuit in 45 which the box is included.

With the foregoing and other objects in view, which will appear as the description proceeds, the invention resides in the combination and arrangement of parts and in 50 the details of construction hereinafter described and claimed, it being understood that changes in the precise embodiment of the invention herein disclosed may be made within the scope of what is claimed with- 55 out departing from the spirit of the invention.

In the accompanying drawings:—

Figure 1 represents a side elevation of the apparatus constituting this invention, the mail box closure being shown closed in 60 full lines with the switch open and open in dotted lines with the switch closed and the indicator shown in operative position in dotted lines and in inoperative position in full lines, and

65 Fig. 2 is a diagram showing the electric circuit used in connection with this apparatus.

In the embodiment of the invention illustrated, a rural delivery mail box 1 is mounted on a suitable support, here shown in the form of a post 2. This box is provided with a hinged closure 3 having an ordinary finger grip 4, said closure being here shown hinged to open downwardly. An electric switch is 70 mounted on the box 1 and comprises a stationary member 5 and a movable member 6, the stationary member 5 being connected with a line wire LW, while switch 6 is connected with a ground wire GW, which extends down and is guided by the post 2 entering the ground at the base thereof. This movable or pivoted switch member 6 is also connected with the closure 3 by means of a flexible element, here shown in the form 75 of a cord 7, said cord being connected at one end with the movable switch in advance of the pivot thereof and at its other end with an apertured ear 8 on the closure, so that when said closure is swung downwardly into 80 open position, as shown in dotted lines, the movable switch member 6 will be brought into engagement with the stationary member 5 and owing to the flexible connection of said member with the closure, will 85 remain in this position after the closure has been closed. It will thus be seen that the switch which is normally open will be closed by the opening of the closure 3 and will remain closed until manually opened.

100 The signal which is to indicate whether or not mail has been placed in the box 1 may be located at any suitable or desired point, preferably about the premises or at the house of the owner of the mail box. This 105 signal comprises an arrow 10 pivotally mounted on the outer face of a casing 11 which may be supported in any suitable or desired manner, and by any means, and which is preferably provided with a closure, 110 not shown, to afford access to the interior thereof. Mounted in this casing 11 is a genera-

tor or magneto G of any suitable or desired construction, and which is provided with a crank handle 12 for actuating it. This generator is connected with a single coil magnet 5 M by a wire W, as is shown clearly in Fig. 2 and the other end of the wire of said magnet is connected with a ground wire GW.

The core 13 of magnet M is arranged in the path of an upstanding flange 14 carried 10 by one end of the arrow 10, said arrow constituting an armature for the magnet so that when the magnet is energized, the core will operate to attract the armature and cause arrow 10 to swing into the position 15 shown in dotted lines in Fig. 1 with its head pointing to the word "mail" carried by the outer face of the casing 11 and which will be occasioned by the passage of a current through the circuit as will be presently described. The line wire LW is connected with a binding post 15 here shown disposed on the lower face of the casing while another binding post 16 is connected with the ground wire GW.

From the above description it will be understood that the switch carried by the mail box is normally open and that the opening of the closure 3 thereof operates to close said switch so that when a current is 20 passed through the circuit by turning of the generator through the crank 12 thereof, the core 13 of magnet M will be energized and thereby attract the armature in the form of the arrow 10 causing it to point to the 25 word "mail" on the casing 11, and thus disclose to the operator the fact that the mail box has been opened presumably for the purpose of placing mail therein, as under ordinary circumstances, said box closure 30 would be secured by a lock, not shown, and which could only be opened by the mail carrier and the owner of the box.

After the mail has been removed from the box 1 and the closure closed, the switch 45 is again opened by disengaging the movable member 6 thereof from the stationary member 5 as shown in full lines in Fig. 1, and should the crank handle 12 then be rotated, the circuit being broken by the opening of 50 the switch, no current will flow through the circuit and consequently the core of the magnet will not be energized and the indicator will remain at inoperative position as shown in full lines in Fig. 1 and thereby 55 demonstrate that no mail has been placed in the box, thus saving unnecessary trips to the box.

The line wire LW may be mounted on any suitable supports and if necessary or 60 desirable may constitute an ordinary string of barb wire constituting one strand of a wire fence, the opposite ends being con-

nected, of course, respectively, with the stationary switch member 5 and with the binding post 15, and by employing the generator 65 for the purpose of supplying a current, all danger of short circuiting and the running down of batteries, which are usually employed in devices of this character will be avoided.

From the above description it will be seen that by the single turning of the crank 12, the owner or patron of the box may readily determine whether or not any mail has been deposited therein, and this means 75 of supplying current which is only used when the switch is in closed position, and the generator actuated, will economize greatly in the expense of an apparatus of this kind and will greatly prolong the life 80 thereof.

From the foregoing description, taken in connection with the accompanying drawings, the advantages of the construction and of the method of operation will be readily 85 apparent to those skilled in the art to which the invention appertains and while I have described the principle of operation of the invention together with the device which I now consider to be the best embodiment 90 thereof, I desire to have it understood that the device shown is merely illustrative and that such changes may be made as are within the scope of the claimed invention.

I claim:

The combination with a mail box having a closure hinged to open downwardly, a switch lever pivoted at one end on said box, a connector uniting said closure with said lever above the hinged connection of the 100 closure with the box, a fixed switch member positioned in the path of said movable member, a normally uncharged line wire connected at one end with said stationary switch member and a ground wire with the 105 movable member, a magneto connected with the other end of said line wire, a ground wire leading from said magneto, an electric magnet interposed in said ground wire and having a core movable therein, a signal in 110 the form of an armature pivoted intermediate of its ends and arranged to be attracted by said core when the magnet is energized, and means for operating said magnet to pass the current through said circuit 115 when desired to ascertain whether the switch is open or closed, said switch being closed by the opening of said closure.

In testimony whereof I affix my signature in presence of two witnesses.

HARVEY R. NEWQUIST.
